Primary Examiner — Ralf Seifert

(57) **CLAIM**

I claim the ornamental design for the zipper-pulling device, as shown and described.

DESCRIPTION

FIG. 1 is a front view of the zipper-pulling device.

FIG. 2 is a left side view of the claimed design.

FIG. 3 is a right side view of the claimed design.

FIG. 4 is a top view of the claimed design; and,

FIG. 5 is a bottom view of the claimed design.

FIGS. 1-3 have a line break indicating that the claimed design is not limited to a particular length of dimension.
